UNITED STATES PATENT OFFICE.

LEVI CLIFTON SPARKS AND AUGUST WILLIAM LOUIS HARTBAUER, OF ST. LOUIS, MISSOURI, ASSIGNORS TO AMERICAN CAR AND FOUNDRY COMPANY, OF ST. LOUIS, MISSOURI, A CORPORATION OF NEW JERSEY.

CAR-WINDOW.

1,078,319.

Specification of Letters Patent. Patented Nov. 11, 1913.

Application filed September 30, 1911. Serial No. 652,177.

To all whom it may concern:

Be it known that we, LEVI CLIFTON SPARKS and AUGUST WILLIAM LOUIS HARTBAUER, residing at St. Louis, Missouri, and being citizens of the United States, have invented certain new and useful Improvements in Car-Windows, of which the following is a full, clear, and exact description, such as will enable others skilled in the art 10 to which it appertains to make and to use the same, reference being had to the accompanying drawings, which illustrate the preferred form of the invention, though it is to be understood that the invention is not 15 limited to the exact details of construction shown and described, as it is obvious that various modifications thereof will occur to persons skilled in the art.

In said drawings: Figure 1 is an elevational view of a portion of a window frame and sash constructed in accordance with this invention. Fig. 2 is a vertical transverse sectional view taken on the plane of line 2—2 of Fig. 1 and looking in the direction 25 of the arrows, the sash being omitted. Fig. 3 is an enlarged horizontal sectional view taken on the plane of line 3—3 of Fig. 1. Fig. 4 is a view similar to Fig. 3, but being taken on the plane of line 4—4 of Fig. 1. Fig. 5 is a view similar to Fig. 3, showing a modified application of the invention, and, Fig. 6 is a detail sectional view taken substantially on the plane of lines 6—6 of Figs. 2 and 4, the sash being omitted.

In the ordinary construction of window frames and sashes therefor, it is necessary to obtain a considerable degree of accuracy between co-working parts so that the sash may properly fit its appropriate place in the frame. With metallic sash it is necessary that the frame be made to almost exact measurements for in such structures the contours can not be readily altered. In steel car construction, to which this invention is particularly designed to be applied, it is only with great care and expense that the window frames can be made of sufficient uniform accuracy to accommodate metallic sashes and this fact has rendered it almost necessary 50 that the sashes be made of wood in order to permit of their being fitted to the inevitable inaccuracies in the frames.

The object of this invention is to provide a means whereby the frames may be con-

structed by ordinary workmen, without the 55 high degree of accuracy above described, and to this end it provides separately formed and adjustably retained guides for the sash, they being mounted in such manner as to be readily adjusted to compensate for de- 60 ficiencies in the frame structure and to correct inaccuracies in the outline of the sash.

A further object is to provide for the ready removal of the sash, or any one of the sashes in a single window, without dis- 65 turbing the retaining means of any other sash. This feature is particularly valuable in car windows comprising the usual double sash.

A further object is to form the guides and 70 the engaging portions of the sash in such manner as to obviate the necessity for the weather strip usually employed.

A further object is to provide, in connection with the removable guides, means for 75 sustaining the weight of the sash in such structures as comprise a fixed upper sash. In these structures the guides serve principally as means for retaining the sashes against lateral play, and as weather strips, 80 and are only utilized as guides when the sashes are being inserted or removed. When it is desired to remove such a sash for re- 85 pairs or for other purposes, the guide is adjusted to permit the sash to fall by gravity from its position.

In the drawings the invention is shown as being applied to a railway car window, but it will be understood that the invention is applicable to the windows of any structure 90 and is of equal value with either fixed or movable sashes.

In the drawings, 1 indicates the inside lining of a car and 2 the outside sheathing thereof. The opposite sides of the window 95 frame and sash, being, constructed identically, only one side is illustrated and will be described in detail. The side of the window frame as 3 extends between the lining 1 and sheathing 2 and is connected, by its opposite vertical edges, to said car parts in any preferred manner. Intermediate said edges the frame is corrugated to form vertical slots or pockets 4—4, into which the adjustable strips or guides 5 are fitted, a pocket and guide being provided for each sash. Each of the guides 5 is of channel cross-section with flanges extending into the space be-

tween the walls of the pockets 4, being so spaced as to have a snug fit between said walls. The web of the channel is preferably formed with a longitudinally extending rib as 6 adapted to be received in a suitable groove 7 formed in the adjacent edge of the window sash 7^a.

At the upper and lower ends of each of the guides 5, and between the flanges thereof, is fixed a U-shape pressing 8, the opposite legs of which are fixed, preferably by welding, to the inner surfaces of said flanges. The intermediate portion of each of the pressings comprises a wall 8^a spaced inwardly from the web of the guide thus forming recesses adapted to receive and retain the heads 9—9 of the adjusting screws 10—10. The walls 8^a—8^a are formed with apertures for the passage of the shanks of the screws and the rear wall of the pocket 4 is apertured and threaded as at 11—11, said apertures 11 extending through reinforcing plates 12—12 fixed to the rear wall of said pocket. The web of the guide or channel 5 is apertured, through the rib 6 thereof, as at 6^a for the insertion of a tool for rotating the adjusting screw. By adjusting one of the screws, the adjacent portion of the guide 5 is moved into or out of the pocket 4. By properly adjusting the screws, top and bottom, and at opposite sides of the sash, the guides are readily moved into close engagement with the sash for correcting inaccuracies in the frame structure. By the same adjustments, an inaccurately formed sash may be inclined slightly to one edge or the other for disposing its bottom edge so as to rest firmly and squarely on the window sill 2^a. By moving the guides into the bottom of the pockets the ribs 6 are disengaged from the grooves 7 and the sash may be lifted out.

The ribs 6 on the guides engaging in the grooves of the window sash, form an effective weather strip.

The guides may obviously be formed with any desired rib contour for engaging correspondingly formed portions of the sash.

When applied to sliding windows the

guides 5 are extended above the upper edge 50 of the sash for a considerable distance to accommodate such sliding and the opposite ends thereof are uninterrupted. When, however, the invention is applied to a stationary sash, as for instance the fixed sash 55 13 in the upper portion of a car window illustrated, the guide is of sufficient length only to slightly more than span the height of the sash and at its lower end is formed with an embossment as 14, adapted to project beneath the lower edge of the sash for supporting the sash. By adjusting the lower end of the guide for moving the embossment 14 into the pocket 4, the sash will be free to fall and is thus readily removed.

In Fig. 5 the invention is illustrated in connection with a wood structure and it will be noted that the essential details are the same as above described. In this structure the metallic member 3 forming the pockets 70 4 are fixed to the relatively smooth face of the wood frame 15, as by screws 16, and suitable recesses as 17—17 are formed in the wood frame for the reception of the projecting ends of the adjusting screws.

What we claim is:

1. The combination with a window frame and a sash, of a guide for said sash adjustable laterally of the edge of the same, said guide including a part disposed in the path 80 of and projecting beneath the bottom of said sash to support the same.

2. The combination with a window frame and a sash, of a guide for said sash adjustable laterally of the edge of the same, and 85 sash supporting means engageable beneath the bottom of the sash and movable with said guide outside the vertical edge of the sash to permit the withdrawal of the sash from the frame.

In witness whereof we have hereunto set our hands in the presence of two witnesses.

LEVI CLIFTON SPARKS.

AUGUST WILLIAM LOUIS HARTBAUER.
